UNITED STATES PATENT OFFICE.

WILLIAM SANFORD HUTCHINSON, OF OYSTER BAY, NEW YORK.

DRUM-BRAKE.

1,152,511.

Specification of Letters Patent.

Patented Sept. 7, 1915.

Application filed January 15, 1915. Serial No. 2,304.

To all whom it may concern:

Be it known that I, WILLIAM S. HUTCHINSON, a citizen of the United States, and a resident of Oyster Bay, Nassau county, New York, have invented a new and useful Improvement in Drum-Brakes, of which the following is a full, clear, and exact description.

My invention relates to improvements in drum brakes such as are peculiarly adapted for use on automobiles, although the brake may be used on other vehicles or for other purposes.

The object of my invention is to produce a simple, powerful, durable, and easily controlled drum brake.

My invention relates particularly to that style of drum brake in which a shoe or shoes is or are arranged within a drum, and forced into contact with the inner rim of the drum. I prefer to apply my invention to a drum of this kind having a spring shoe extending substantially around the inner surface of the drum rim, and when the shoe is expanded it engages the rim of the drum, and when contracted it leaves the drum clear. In connection with means for expanding the shoe, I employ stationary blocks supported within the drum rim and shoe, and guiding devices operating in connection with the blocks and serving to force the shoe with great power against the rim of the drum, while such devices permit the shoe to be easily released and contracted.

Reference is to be had to the accompanying drawings forming a part of this specification, in which similar reference characters indicate corresponding parts in all the views.

Figure 1 is a cross-section of a drum and my improved brake as applied to the hub and axle of an automobile. Fig. 2 is a cross-section on the line 2—2 of Fig. 1, showing the guiding devices in detail. Fig. 3 is a view similar to Fig. 2 but showing slightly modified guiding and actuating devices, and Fig. 4 is a view similar to Fig. 3 but showing still another modification of the invention.

To illustrate the application of my invention I have shown a drum 10 which is of substantially the usual type and which is applied to the hub 11 of an automobile wheel, which is connected as usual with an axle 12. Obviously the particular style of the drum is not material. I prefer to use the single shoe 13 of spring material, which is ar-

ranged within the drum rim and concentric therewith, this shoe having preferably a stiffening rib 14 about centrally thereon and on the inner side. When a single shoe is used I prefer to connect the ends by an extensible spring 15. Any suitable means can be used for expanding the shoe so as to put it in contact with the drum rim, and I do not limit the invention to any particular device of this kind. I have shown a means which I do not here claim, comprising a bent arm 16 which is pivoted to one end of the shoe 13, and is connected pivotally by means of a link 17 with the opposite shoe end, the link being pivoted at the bend of the arm, and the arm 16 has its inner end connected pivotally by means of the link 18 with a crank 19 on the shaft 20. This shaft extends parallel with the axle 12, through a stationary plate 23, which can be supported in any convenient way, but which is shown fixed to the housing 23^a of the axle 12. The shaft 20 connects by the crank 21 with the ordinary brake rod 22 so that when the rod is actuated in the usual or any preferred manner, the shaft 20 may be rocked, and through the medium of the connecting parts, the shoe 13 may be expanded or contracted. Means has to be provided to guide the shoe 13, and to force it with sufficient power against the drum rim. I have illustrated several ways of accomplishing this result, and in Fig. 2 I show a series of blocks 24 which are fast to the plate 23, while opposite the blocks are triangularly shaped bosses 25 which are fixed to the shoe and which enter correspondingly shaped notches in the blocks 24. Consequently when the shoe is expanded so as to frictionally engage the drum 10, the bosses 25 will ride upon the inclined walls of the blocks 24, the blocks and walls having a cam action, and the shoe can be locked tight to the drum 10. It will be seen that this construction has the advantage of operating in either direction, that is to say, whether the drum 10 is rotating either forward or backward, the shoe will have the same frictional contact and the same freedom to lock securely to the drum.

It will be evident that many forms of fixed abutments within the drum and shoe, and many forms of engaging members for such abutments, can be used and connected to the shoe without affecting the principle of the invention. To illustrate this I have shown slight modifications in Figs. 3 and 4. In

Fig. 3 the stationary blocks 26 have their outer surfaces, that is the sides next the shoe 13, crescent shaped, and arms 27 are secured to the shoe, and converge and have a common pivot on the rolling abutment 28 which rides in the concave side of the block 26. Thus when the shoe is expanded, the roller 28 can ride upon the curved incline of the block 26 and permit the same freedom of movement of the shoe so that it will lock against the drum, while the contraction of the shoe will cause the rollers 28 to ride back to the lowest point of the concavity of the block. In Fig. 4 the same principle is carried out. In this instance the blocks 29 are secured to the plate 23 or to some other fixed support, while the members 30 are arranged opposite the blocks and have semi-circular projections or bosses 31 fitting corresponding recesses in the blocks 29. The members 30 connect by arms 32 with the shoe 13 to which they are pivoted, and the action is precisely as already described, that is to say, when the shoe is expanded, the rounded projections 31 will ride upon the corresponding parts of the blocks 29, and when the shoe is contracted they will sink back to their normal position. In each instance it will be observed that the frictional contact of the shoe with the drum, which is caused in the first instance by the brake rod as already explained, will cause the drum and shoe to cohere, and this action is accentuated by the connection between the shoe and the stationary abutment blocks within the shoe. As before remarked, it will be evident that the particular form of this connection between the stationary parts within the shoe and the shoe itself, can be changed without affecting the principle of the invention.

I claim:—

1. A brake comprising a rotatable drum, a shoe arranged within the drum and adapted to impinge upon the rim of the drum, said shoe having a limited rotary movement in both directions with the drum, a stationary abutment between the shoe and the drum axis, said abutment having guides diverging

toward the drum rim, and a member connected with the shoe and in engagement with the guides whereby the movement of the shoe with the drum in either direction forces the shoe against the drum rim. 50

2. A brake comprising a rotatable drum having a rim, a shoe concentrically arranged within the drum and adapted to impinge upon the drum rim, means independent of the setting mechanism for moving the shoe into and out of frictional engagement with the drum rim, a stationary abutment between the shoe and the axis of the drum, fixed guides on the abutment directed to set the shoe against the rim, and members connected to the shoe and arranged to follow the guides on the fixed abutment, whereby the rotation of the drum in either direction will cause the shoe members to follow their guides and set the shoe forcibly against the rim. 60

3. A brake comprising a rotatable drum, a shoe arranged within the drum, means for moving the shoe toward and away from the drum, a stationary abutment between the shoe and the axis of the drum, said abutment having oppositely inclined guiding surfaces diverging toward the drum, and a member on the shoe following the guiding surfaces of the fixed abutment, said guiding surfaces acting to force the shoe outward against the rim whereby the shoe and rim are in frictional engagement. 70

4. A brake comprising a rotatable drum, an expandable shoe arranged concentrically within the drum and adapted to impinge on the drum rim, means for expanding and contracting the shoe, stationary abutment blocks arranged within the shoe and between the shoe and the axis of the drum, said blocks having guiding surfaces diverging toward the shoe, and members secured to the shoe and constructed to follow the guiding surfaces of the abutment blocks. 80
